UNITED STATES PATENT OFFICE

168,096

DOLL

Jutta C. Hula, Pittsburgh, Pa.

Application October 4, 1951, Serial No. 16,831

Term of patent 3½ years

(Cl. D34—4)

To all whom it may concern:

Be it known that I, Jutta C. Hula, a citizen of the United States, residing at Pittsburgh, Pennsylvania, have invented a new, original, and ornamental Design for a Doll, of which the following is a specification, reference being had to the accompanying drawing, forming a part hereof.

Fig. 1 is a front view of a doll showing my design; and Fig. 2 is a side view of the doll.

I claim:

The ornamental design for a doll as shown.

JUTTA C. HULA.
